UNITED STATES PATENT OFFICE.

JOSEPH C. CARLSON, OF DETROIT, MICHIGAN.

FLYCATCHER.

1,324,727.

Specification of Letters Patent.

Patented Dec. 9, 1919.

Application filed August 25, 1919. Serial No. 319,532.

To all whom it may concern:

Be it known that I, JOSEPH C. CARLSON, a citizen of the United States of America, residing at Detroit, in the county of Wayne 5 and State of Michigan, have invented new and useful Improvements in Flycatchers, of which the following is a specification.

This invention relates to insect traps, particularly to fly catchers, and has for its object 10 the provision of an attachment adapted to be disposed upon the top of a garbage can and so constructed as to hold a sheet of sticky fly paper provided with perforations through which the odors from the garbage 15 can may escape to attract the flies and through which the flies will endeavor to pass in order to gain access to the garbage, the flies being caught and held in this attempt.

An important object is the provision of 20 an attachment of this character with which is associated a cover member designed for protecting the sticky fly paper against rain and also designed to prevent cats and other animals from gaining access to the garbage, 25 this cover member being provided with a plurality of holes through which flies may enter and be caught, as above mentioned.

An additional object is the provision of a 30 device of this character which will be simple and inexpensive in manufacture, highly efficient in use and a general improvement in the art.

With the above and other objects and advantages in view, the invention consists in 35 the details of construction and arrangement to be hereinafter described and claimed and illustrated in the accompanying drawings, in which:

Figure 1 is a side elevation of the upper 40 portion of a garbage can equipped with my complete device,

Fig. 2 is a longitudinal sectional view therethrough, and

Fig. 3 is a horizontal sectional view on the 45 line 3-3 of Fig. 2, showing the sticky fly paper in plan.

Referring more particularly to the drawing, the letter A designates a garbage can of ordinary construction and B designates my 50 device as a whole.

In carrying out my invention I provide a cylindrical member open at its top and bottom and designated by the numeral 10. This cylindrical member as well as all the other 55 parts of the device is formed of sheet metal, preferably galvanized iron and this cylin-

drical member has its upper and lower edges rolled. Secured within the member 10 is a disk member 11 which is provided at its outer edge with a depending flange 12 secured to the lower portion of the member 10 and which is provided with a central hole 13. When the member 10 is disposed upon the top of the garbage can the disk member 11 will seat upon the top of the can for holding my device in proper position. Disposed upon the disk member 11 is a sheet 14 of sticky fly paper which is provided throughout its area with a plurality of small holes 15. When this sheet of fly paper is disposed upon the disk member 11, the odors rising from the garbage within the can will pass through the holes 15 and attract flies, some of which will alight upon the sticky fly paper and be caught thereby and others of 75 which will attempt to pass through the holes 15 and be caught in such attempt. The portion of the device thus far described may be used by itself though I preferably make use of a cover member including a cylindrical 80 portion 16 having a handle 17. Depending from the cylindrical portion 16 is a flange 18 which engages exteriorly upon the upper portion of the cylindrical member 10 and the shoulder formed at the juncture of the 85 portion 16 with the flange 18 engages upon the upper edge of the member 10 for holding this cover in proper position. The top of this cover 16 is closed but the outer periphery of the portion 16 is provided with a 90 series of holes 19 through which flies may enter.

From the foregoing description and a study of the drawing it will be seen that I have provided a very simple device which 95 may be attached to a garbage can to serve as a cover therefor and which is provided with means whereby the flies attracted by the odors will be caught, the device being so constructed as to exclude rain and to prevent the entrance of cats or other animals.

While I have shown and described the preferred embodiment of my invention, it is of course to be understood that I reserve the right to make such changes in the form, 105 construction, and arrangement of parts as will not depart from the spirit of the invention or the scope of the subjoined claims.

Having thus described my invention, I 110 claim:

1. A garbage can attachment comprising a cylindrical member adapted for disposi-

- tion upon the top of a garbage can and pro-
vided internally with a supporting member
having an opening therein, a sheet of sticky
fly paper disposed upon said supporting
member and provided with a plurality of
holes, and a cover member disposed upon
said cylindrical member to form a closure
therefor and provided in its periphery with
a plurality of holes.
- 10 2. In combination with a garbage can, a
fly catching device comprising a cylindrical
member adapted for disposition upon the top
of a garbage can in externally encircling re-
lation thereto, a disk member extending
15 transversely of said cylindrical member in-
termediate the ends thereof and provided
with a central opening, and a sheet of sticky
fly paper supported upon said disk member
and provided with a plurality of holes.
- 20 3. In combination with a garbage can, a
fly catching device comprising a cylindrical

member adapted for disposition upon the
top of a garbage can in externally encircling
relation thereto, a disk member extending
transversely of said cylindrical member in-
termediate the ends thereof and provided
with a central opening, and a sheet of sticky
fly paper supported upon said disk member
and provided with a plurality of holes, and
a cover member including a cylindrical body 30
having a closed top wall and having formed
upon its lower edge a flange of larger dia-
meter than the body engaging exteriorly upon
the upper portion of said cylindrical mem-
ber, the juncture of said flange with said 35
body defining a shoulder engaging upon the
upper edge of said cylindrical member and
the periphery of said body portion being
provided with a plurality of holes.

In testimony whereof I affix my signature. 40

JOSEPH C. CARLSON.
